UNITED STATES PATENT OFFICE

2,416,762

MULTICYLINDER OPPOSED-PISTON INTERNAL-COMBUSTION ENGINE

Hans Lieberherr, Winterthur, Switzerland, assignor to Sulzer Frères, Société Anonyme, Winterthur, Switzerland

Application September 20, 1944, Serial No. 554,942
In Switzerland November 20, 1943

4 Claims. (Cl. 123—51)

1

The invention relates to a multi-cylinder opposed-piston internal combustion engine in which in particular the pistons of each working cylinder act through two crankshafts upon a main shaft. It consists in that the middle part of the cylinder on both sides of the engine axis is formed by a continuous supporting wall. The necessary members (fuel valve, starting-air valves, safety valve, ignition tubes) can then be fitted parallel to each other and at right angles to the direction of the engine axis.

In known opposed-piston engines the valves (fuel valve, starting valve, safety valve) are built in radially. This not only caused difficulty in the machining of the cylinder block, but led above all to an unfavourable flux of force in the part occupied by the valves and in the transition to the adjoining parts, and further to an undesirable reduction of the moments of inertia and resistance in the middle part of the cylinder block. This weakening and reduction of the rigidity of the block makes itself unpleasantly felt in particular in large engines. Furthermore, the transverse stiffness of the block is impaired and the creation of transverse vibrations encouraged.

The invention surmounts these difficulties in that the cylinder jacket in the middle part is laterally bounded by a continuous supporting wall, into which it is preferable to build the necessary members parallel to each other and at right angles to the engine axis. In this way higher moments of resistance and inertia are obtained over the whole depth of the block. Further, machining is rendered much simpler and the pipes can be more easily conducted to the respective members. Finally, the parallel arrangement of the valves permits the distance between two adjoining cylinders to be decreased, as when a valve is removed there is no need for attention to be paid to the adjoining valve also obliquely arranged.

One embodiment of the invention is diagrammatically shown in the drawing.

Fig. 1 shows the design hitherto customary for the middle part of the cylinder of opposed-piston internal combustion engines.

Fig. 2 shows the design as proposed in the invention.

Fig. 3 is a section through an engine constructed according to the invention on a plane which includes the axis of a cylinder and is perpendicular to the common middle plane which includes the axes of all cylinders.

In known opposed-piston engines (Fig. 1) the 55 with two pistons running in each cylinder, char-

2

necessary members, for instance the fuel valves 1 and 4, the starting-air valve 2, the safety valve 3 and any ignition tubes which may be required, are fitted radially into the cylinder 5. This not only renders the machining of the cylinder block difficult, but also reduces the moments of inertia and resistance in the middle part of the block.

In the execution shown in Fig. 2, in contrast to this, the cylinders 8 are built into the cylinder block 9, which has on both sides a continuous supporting wall 10. The fuel valve 11 is arranged perpendicular to the axis of the engine. The starting valve 13 of the internal combustion engine also runs perpendicular to the direction of the main axis of the engine.

The fuel valve 11 is inserted in a casing 14. On the starting valve 13 is provided a valve plate which is influenced by some control system. It will be understood that more than one fuel valve may be used in each cylinder and that other necessary members may be arranged in the described manner in the continuous supporting walls 10, for example, ignition tubes or indicator cocks.

As shown in Fig. 3, the cylinder liner 8 is provided with inlet ports 17 and 18 for the scavenging and charging air and with outlet ports 19 for the exhaust gases. This cylinder liner may be fastened to the block 9 by any securing means such as the fixing screws 12 of Fig. 2 or the pins 28 and 29 of Fig. 3 which cooperate with groove 27 and contact surface 30 respectively. The opposed pistons 20 and 21 are shown at outer dead center; their position at inner dead center, 20', 21', is indicated by broken lines. The middle part of the cylinder block is bound by two continuous parallel supporting walls 10, which are parallel to the common middle plane of the engine. Cooling of the engine is provided by circulation of coolant through cooling spaces 22, 23 which are inter-connected with cooling space 25 by passages 24. Lubrication of pistons and rings is provided through oil pipes 26.

The positions of fuel valve 14 and starting valve 13 are, as shown in Fig. 2, in planes parallel to and displaced laterally from a plane that includes the axis of the cylinder and is perpendicular to the common middle plane that includes the axes of all cylinders. In the engine illustrated in Fig. 3 these necessary members are also perpendicular to the common middle plane of the engine.

I claim:

1. Multi-cylinder internal combustion engine

acterised in that the middle part of the cylinder not swept by the pistons on both sides of the engine axis is formed by a continuous supporting wall and a plurality of injection or starting members in the middle part of the cylinder with their axes parallel to each other.

2. Multi-cylinder internal combustion engine as claimed in claim 1, characterised in that the fuel valve and starting-air valve are arranged parallel to each other at right angles to the axis 10 of the engine and in a plane parallel to the cylinder axis and spaced to the side thereof.

3. A multicylinder internal combustion engine with two pistons running in each cylinder and a plurality of injection or starting members in the 15 middle part of said cylinders not swept by said pistons, said middle part being bounded by continuous supporting walls which run parallel to the common middle plane that includes the axes of all cylinders and in which said injection and starting members are arranged parallel to each other and perpendicular to said common middle plane.

4. A multicylinder internal combustion engine with two pistons running in each cylinder and 20 a plurality of injection or starting members in the middle part of said cylinders not swept by

said pistons, said middle part being bounded by continuous supporting walls which run parallel to the common middle plane that includes the axes of all cylinders and in which said injection and starting members are arranged to lie in planes parallel to and laterally displaced from the planes that include the axis of each cylinder and are perpendicular to said common middle plane.

HANS LIEBERHERR.
